UNITED STATES PATENT OFFICE.

JOHN H. PAGE, OF DETROIT, MICHIGAN.

DESIGN FOR A WALL CLOCK.

Application filed January 31, 1927. Serial No. 20,551. Term of patent 14 years.

To all whom it may concern:

Be it known that I, JOHN H. PAGE, a citizen of the United States, residing at Detroit, in the county of Wayne and State of Michigan, have invented a new, original, and ornamental Design for Wall Clocks, of which the following is a specification, reference being had to the accompanying drawing, forming part thereof.

Figure 1 is a front elevation of a wall clock, showing my new design; and Figure 2 is a side elevation.

I claim:—

The ornamental design for a wall clock, as shown.

JOHN H. PAGE.
